UNITED STATES PATENT OFFICE.

DANIEL KOPS, OF NEW YORK, N. Y.

BRASSIÈRE.

1,272,940.

Specification of Letters Patent. Patented July 16, 1918.

Application filed May 11, 1918. Serial No. 233,833.

To all whom it may concern:

Be it known that I, DANIEL KOPS, a citizen of the United States, residing in the borough of Manhattan, city, county, and State of New York, have invented an Improvement in Brassières, of which the following is a specification.

This invention relates to a brassière and more particularly to a brassière in conjunction with which there is employed a pad member such as illustrated in Letters Patent No. 1,252,124, dated January 1, 1918, for controlling, reducing, and massaging the flesh which oftentimes accumulates beneath the busts in the use of the now more or less prevalent low busted corsets. In the patent aforesaid I have shown and described a pad member for this purpose which is connected along its lower edge to the lower front edge of the brassière or similar garment and is fixedly secured in position therein so that the position of this pad member is dependent entirely upon the adjustment of the brassière to position on the body of the wearer. Now, the object of the present invention is the provision of a pad member for use with a brassière which is centrally associated with the front section of the garment and is adjustable to position with the adjustment of the garment to place so as to vary the tension on the pad and consequently the pressure exerted thereby against the underlying parts of the body of the wearer.

The brassière in which my present invention is embodied is illustrated in the accompanying drawing in which:

Figure 1 is a perspective view illustrating the improved brassière.

Fig. 2 is an enlarged plan of the inner side of the brassière.

Fig. 3 is a partial plan showing the parts in a different position to that illustrated in Fig. 2.

Fig. 4 is a view similar to Fig. 2, showing another form of the invention, and

Fig. 5 is an enlarged cross section on line 5—5 Fig. 4.

Referring to the present invention, as shown in Figs. 1, 2 and 3, the brassière in which the same is embodied comprises a front member 10, which is continuous and adapted to act as a bust supporter and which as illustrated may be made in sections 11, 12 and 13. This garment also includes a back member 14 made in sections 15 and 16 and a corresponding back member 17 made in

sections 18 and 19. One vertical edge of the back member 14 is fitted with a reinforcing strip 20 in which there is a series of eyelets 21. The adjacent edge of the front member 10 is fitted with a reinforcing strip 22 in which there is a series of eyelets 23. Laces 24 are threaded through the eyelets 21 and also through the eyelets 23 and are looped on the inner side of the garment and connected to one end of a tie tape 25 as indicated at 26.

Similarly on the other side of the garment one vertical edge of the back member 17 is provided with a reinforcing strip 27 provided with series of eyelets 28. The adjacent edge of the front member 10 is provided with a reinforcing strip 29 in which there is a series of eyelets 30. Laces 31 are threaded through the eyelets 28 and also through the eyelets 30 being looped on the inside of the garment, and one end of a tie tape 32 is secured to the loops as indicated at 33. The tie tapes 25 and 32 in this form of the invention pass through tape holes 34 provided therefor in a reinforcing strip 34 fixed in the lower front central portion of the garment, to which there may also be secured a strap 36 and a tie member or buckle 37 adapted to be secured to the corset 35 or other garment to prevent the brassière from creeping upwardly on the body of the wearer. As will be understood, these tie tapes 25 and 32 are drawn together to adjust the parts of the brassière on the body 90 of the wearer and are connected by being tied or otherwise to secure the garment in position.

The parts of the garment hereinbefore described are similar in many if not in all respects to those heretofore employed by me in different forms of brassières, and the present invention relates more particularly to the construction and adjustment of the pad member now to be described. This pad member as illustrated, preferably consists in a strap 38 which may be suitably reinforced and is secured in a central position to the front member of the brassière, in this form of the invention by lines of sewing indicated at 39 and 40 at the respective ends of the reinforced strap. This pad member also includes series of straps 41, which may or may not be reinforced, and which are connected at corresponding ends 105 in the strap 38 in which they are spaced from one another. These straps 41 con-

verge at their opposite ends at which they are connected along lines of stitching 42 at one end of a strap member 43. The other end of the strap member 43 is provided with eyelets 44 through which one set of the laces 24 are also threaded. Similarly on the other side of the garment there is a corresponding set of straps 45, which, may or may not be reinforced, and which at corresponding ends are secured to the strap 38 in the same positions as the adjacent ends of the straps 41. At their opposite ends these straps 45 converge and are connected to a strap 46 at one end thereof by lines of stitching 47 or otherwise. In the opposite end of this strap 46 there are eyelets 48 through which one set of the laces 31 is also threaded.

One edge of the back member 14 may be fitted with a reinforcing strip 49 in which there is a series of eyes 50 to be engaged by a series of hooks 51 secured in the reinforcing strip 52 on the corresponding edge of the back member 17 and by which as will be understood, the parts of the garment are connected for use. As is also customary in such garments the same may be provided with shoulder straps indicated at 53 and 54.

As will now be apparent in the use of this garment when placed in position on the body of the wearer, the parts may be adjusted by drawing the tie tapes 25 and 32 and the garments secured in position by fastening these tie tapes to one another. In so doing inasmuch as one set of each of the series of laces 24 and 31 is adjustably connected in the straps 43 and 46 with which the pad is connected, the adjustment of the garment to position will also cause an adjustment of the pad to place so that the tension on the pad and consequent pressure exerted thereby on the underlying parts of the body of the wearer may be varied, depending upon the tension placed on the laces connecting the pad member to the adjustable lacing devices which connect the front and back members of the garment to one another, these adjustments being made along the axillary lines of the garment.

The form of the invention shown in Figs. 4 and 5, is similar in all respects to that shown in Figs. 1, 2 and 3, with the exception of the manner in which the pad member is connected at its lower edge to the front central portion of the body of the brassière. In the structure shown in Figs. 1, 2 and 3, as hereinbefore described, this pad member is connected to and adjustable at its ends with the lacing devices by which along the axillary lines the garment is adjusted to position on the body of the wearer, whereas in Figs. 4 and 5, the same condition is maintained with the additional adjust-

able feature of having the pad adjustable at the lower central portion thereof by associating the same with the tie tapes as hereinafter described.

Inasmuch as the structure of the brassière shown in Figs. 4 and 5 is similar to that shown in the other figures with the exceptions hereinbefore noted, the same reference characters have been applied to Figs. 4 and 5 as those used to describe the structure shown in Figs. 1, 2 and 3, excepting however, the central member of the reinforced strap of the pad and devices by which at the lower end thereof it is associated with the tie tapes. In Figs. 4 and 5, the central reinforced strap or pad is indicated at 56. At its upper end this is attached to the front central portion of the body of the brassière along the lines of stitching 57 or otherwise. The lower end of the reinforced strap 56 however is not directly connected with the lower front central portion of the body member of the brassière. On the contrary, at its lower end this reinforced strap 56 is provided with eyelets 58 and 59 in positions 85 similar to those of the tape holes 35 in the reinforced strap 38 so that these eyelets 58 and 59 may be so placed as to register with the eyelets or tape holes 35. In this structure the tie tape 25 is passed through the eyelet 58 also through one of the tape holes 35, while the tie tape 32 is passed through the eyelet 59 and the other tape hole 35. Also, in this form of the invention, instead of providing eyelets in the ends of the extension straps 43 and 46, so that the same is associated with predetermined laces, I may employ as clearly indicated in Fig. 4, clasp members, the parts 60 and 61 thereof being separable with the part 60 attached to the extremity of the straps and the part 61 being a loop through which one of the sets of laces passes. As will now be understood, this form of pad member with its attachment to the garment is adjustable not only at the ends thereof, but also at the lower front central portion thereof, the adjustment being effected simultaneously with the adjustment of the parts of the garment to position on the body of the wearer, and by 115 the same lacing devices and tie tapes by which this adjustment is effected.

I claim as my invention—

1. In a brassière or similar garment, adjustable to position on the body of the wearer, a pad member placed centrally to the lower front central portion of the garment and extending laterally to both sides thereof, and means for applying tension to the said pad member in adjusting the garment to position for use.

2. A brassière comprising a front member, a back member, means for adjustably connecting the front and back members to one another at substantially the axillary

lines of the garment, a pad member secured to the lower front central portion of the front member and extending laterally therefrom, and means for varying the tension of the pad member to correspondingly vary the pressure applied thereby to the underlying parts of the body of the wearer.

3. A brassière comprising a front member, a back member, a pad member secured to the lower front central portion of the front member and extending laterally therefrom, and lacing devices for adjusting the front and back members to position along the axillary lines of the garment and simultaneously adjusting the ends of the said pad member to position to vary the tension thereon and consequently the pressure exerted thereby against the underlying parts of the body of the wearer.

10 4. A brassière comprising a front member, a back member, a pad member placed centrally in the lower front central portion of the front member and extending laterally on both sides thereof and terminating in extension straps, a series of laces passing through the adjacent edges of the front and back members with predetermined laces also passing through the extension straps of the said pad member, and tie tapes secured to the said laces for adjusting the front and back members of the garment to position along the axillary lines thereof and simultaneously

adjusting the extension members of the said pad to position to vary the tension thereon and consequently the pressure applied thereby to the underlying parts of the body of the wearer.

5. A brassière comprising a front member, a back member, a pad member placed centrally in the lower front central portion of the front member and extending laterally therefrom, an extension strap secured to the respective ends of the pad member which at its upper end is secured to the body member of the brassière and at its lower end is free therefrom, a series of laces passing through the adjacent edges of the front and back members with predetermined laces also passing through the adjacent ends of the extension straps of the said pad member, and tie tapes secured to the said laces and passing through the lower end of the central portion of the said pad member and also through the lower front central portion of the body of the brassière so that in drawing the tie tapes together the front and back members are adjusted to position on the body of the wearer and simultaneously the pad member is adjusted to position at its ends and also in the lower front central portion thereof.

Signed by me this 3d day of May, 1918.

DANIEL KOPS.
